GARMENT FOR BOYS

Betty Rubin, Brooklyn, N. Y., assignor to Eagle Boys Suit Corporation, New York, N. Y., a corporation of New York

Application October 9, 1933, Serial No. 692,775
Renewed August 8, 1935

6 Claims. (Cl. 2—228)

My invention relates generally to the association of an inner or outer garment, such as a pair of drawers, with an outer garment, such as a pair of trousers.

5 In one of its aspects my invention relates to an arrangement whereby an inner garment and an outer garment may be associated together and in another aspect it relates to an arrangement whereby the garments so associated may be supported from the waist and the hips and when necessary can be conveniently and rapidly removed from such support while in their associated relation.

10 In still another aspect, my invention relates to an arrangement for contracting the waist band portion of a garment adapted to be supported from the waist or hips by such contraction.

15 My invention is particularly intended for garments for boys, such as trousers and the corresponding articles of underwear, and is therefore so illustrated in the drawing and described in the specification.

20 It is the general object of my invention to provide for the association in a novel manner, of boys' trousers and drawers.

25 It is the further object of my invention to provide a construction whereby garments of the character referred to may be supported from the waist and from the hips, and, more particularly, an arrangement whereby two such garments may be maintained and associated for ready assembly and disassembly, and may be supported from the hips and the waist and readily removed therefrom as a unit while in such associated relation.

30 For the attainment of these objects and such other objects as may hereinafter appear or be pointed out, I have illustrated an embodiment of my invention in the drawing, wherein:

35 Figure 1 is a view showing an inner and an outer garment in assembled relation;

40 Figure 2 is a sectional view on an enlarged scale on the line 2—2 of Figure 1 looking in the direction of the arrows; and

45 Figure 3 is a perspective view showing in detail my invention as applied to an outer and inner garment.

50 Referring to the drawing in detail, I have there shown a pair of trousers 10, such as customarily worn by small boys and having a waist-band portion 12, and a pair of drawers 14 adapted for small boys' wear, having a waist-band portion 16.

55 For the purpose of retaining the trousers in place, I have shown at 18 a restricting element in

the form of an elastic band. This restricting element is secured to the trousers as shown at 20 in any preferred manner as for instance by stitching. This leaves the outer ends of the elastic band free, and secured to each of the ends is shown a button 22. On each side of the securing point 20 of elastic band is located a transverse slit 24, which is wide enough to permit the insertion therethrough of the ends of the elastic band. In the waist band portion of the drawers 10 are located the transverse slits 28 which are intended to register with the transverse slits 24 of the trousers. These slits are also adapted for the insertion therethrough of the end portions of elastic band 18 and when one end of the elastic 15 band is inserted successively through slits 24 and 28 and the button 22 thereon is successively inserted through button-holes 30 and 26, it will be seen that the drawers and the trousers are then secured together, as clearly shown in Figure 2. 20 It will of course be understood that normally all ends of all the bands 18 will engage their appropriate button-holes. It will further be noted, as appears in Figure 2, that the distance between the buttons 22, as measured along elastic band 25 18, is less than the distance between the button-holes 26 or 30, measured along their respective garments. The resulting effect can be clearly observed in Figure 2, in which the trousers and drawers are shown gathered in in relation to the band. The normal length of the bands 18, is proportioned so that they contract the waist-band of the drawers and trousers to a girth less than that necessary to encircle the 30 waist of the wearer and so that when the garment is positioned on a wearer, the bands will yield and hold the garment about the waist and fit the wearer by elastic tension. The gathered-in folds of the outer and inner garments, shown in Figure 2, will in the meanwhile provide for the 35 necessary expansion of these garments.

40 It will be noted that whereas the slits 24 and 28 are disposed transversely to the waist band, which is obviously their logical disposition to permit passage of the elastic band therethrough, the button-holes 26 and 30 are disposed longitudinally or horizontally in relation to said waist-band. Such disposition permits lateral adjustment between the various parts connected by the buttons 22, namely the bands 18 and the 45 50 waist-bands 14 and 16. The advantage of such lateral adjustability is obvious and needs no explanation.

45 While in Figures 2 and 3 I have shown the elastic band 18 as connecting or adapted to con- 55

nect the inner and outer garment, it is obvious that it may perform the same function in relation to one garment only. This will appear from inspection of Figure 2. If, in imagination, the 5 waist band 16, be eliminated in Figure 2, the capacity of the band 18 for supporting the trousers 10 will then appear clearly.

While I have shown and described my invention in relation to one embodiment thereof, it 10 will be obvious that the same may be embodied in many other forms, as will be apparent to those skilled in the art, without departing from the spirit thereof, as defined in the claims appended hereto.

15 It will be understood that the drawers 14 is a completely operative unit as such by itself and that the same is true of the trousers 10 and that the two are illustrated as modified only insofar as a ready association of the two into a single 20 assembly and a disassociation of the two into individual units calls for such modification. Each garment is therefore replaceable in the assembly at will and is subject to washing or other treatment by itself.

25 Having thus described my invention and illustrated its use, what I claim as new and desire to secure by Letters Patent is:

1. In boys' wear, an inner bifurcated nether garment having a waistband portion and a body portion and an outer bifurcated nether garment having a waist-band portion and a body portion and adapted for surrounding the inner garment, means carried by said outer garment on each side and on the waist-band portion thereof for elastically and conjunctively supporting said garments from the waist and the hips of a wearer, said means comprising extensible elastic bands of substantial width each permanently fastened at its middle portion to the outside of the waist-band portion of said outer garment and carrying a button adjacent each of its ends, a transversely disposed slit of sufficient width to receive therethrough said elastic bands, positioned in the waist-band portion of said outer garment on each side of the middle portion of said elastic bands, and adapted to permit passage therethrough of one of the button-carrying ends of one of said bands, a transverse slit in the waist-band portion of said inner garment registering with each of 30 said transverse slits in said outer garment, and likewise adapted to receive therethrough one of said button-carrying ends, laterally extending slits in the waist-band portion of said inner garment, each adapted to receive one of the buttons carried by said elastic bands, a laterally extending slit in the waist-band portion of said outer garment, adapted to register with each of said laterally extending slits in the inner garment, and to receive therethrough one of the buttons carried by said elastic bands after it has been inserted through the registering slit of the inner garment, the distance between the buttons of each band being less than that between the lateral slits adapted to receive said buttons, whereby 35 said bands are free to be extended until their length equals the distance between said last-mentioned slits.

2. In boys' wear, a pair of drawers having a waist-band portion and a body portion, and a pair of trousers having a waist-band portion and a body portion and adapted to surround said drawers, means carried by said trousers on the waist-band portion thereof for elastically and conjunctively supporting said garments from the 40 waist and the hips of a wearer, said means com-

prising an extensible elastic band permanently fastened intermediate its ends to the outside of the waist-band portion of said trousers and carrying a button adjacent each of its ends, a slit, of sufficient width to receive therethrough said elastic band, positioned in the waist-band portion of said trousers on each side of the middle portion of said elastic band, and adapted to permit passage therethrough of one of the button carrying ends of said band, a slit in the waist-band portion of said drawers registering with each of said slits in said trousers, and likewise adapted to receive therethrough one of said button-carrying ends, slits in the waist-band portion of said drawers, each adapted to receive one of the buttons carried by said elastic band, a slit in the waist-band portion of said trousers adapted to register with each of said button-receiving slits in the drawers, and to receive therethrough one of the buttons carried by said elastic band after it has been inserted through the registering slit of the drawers, the distance between the buttons of said band being less than that between the lateral slits adapted to receive said buttons whereby said band is free to be extended until its length equals the 45 distance between said last-mentioned slits.

3. In combination, an inner garment having a waist-band portion and a body portion and an outer garment having a waist-band portion and a body portion and adapted to surround said inner garment, means carried by said outer garment on each side and on the waist-band portion thereof for elastically and conjunctively supporting said garments from the waist and the hips of a wearer, said means comprising an extensible 50 elastic band of substantial width fastened at its middle portion to the outside of the waist-band portion of said outer garment and carrying buttons on its free portions, a transversely disposed slit of sufficient width to receive said elastic band positioned in the waist-band portion of said outer garment adjacent the free end portions of said elastic band, and adapted to permit passage therethrough of the ends of said band, a transverse slit in the waist-band portion of said inner 55 garment registering with each of said transverse slits in said outer garment, and likewise adapted to receive therethrough said ends, button-holes in the waist-band portion of said inner garment, each adapted to receive one of the buttons carried by said elastic band, a button-hole in the waist-band portion of said outer garment adapted to register with each of said button-holes in the inner garment, and to receive therethrough one of the buttons carried by said elastic band 60 after it has been inserted through the registering button-holes of the inner garment, the distance between the buttons of said band being less than that between said button-holes whereby said band is free to be extended until its length equals the distance between said last-mentioned slits.

4. In combination, an inner garment and an outer garment surrounding said inner garment, means carried by said outer garment for elastically and conjunctively supporting said garments 65 from the waist and the hips of a wearer, said means comprising an extensible elastic band of substantial width fastened to said outer garment and carrying buttons on its free portions, a slit of sufficient width to receive said elastic band 70 positioned in said outer garment adjacent the free end portions of said elastic band, and adapted to permit passage therethrough of the ends of said band, a slit in said inner garment registering with each of said slits in said outer garment, 75

- and likewise adapted to receive therethrough said ends, button-holes in the waist-band portion of said inner garment, each adapted to receive one of the buttons carried by said elastic band, a button-hole in said outer garment adapted to register with each of said button-holes in the inner garment, and to receive therethrough one of the buttons carried by said elastic band after it has been inserted through the registering button-hole 5 of the inner garment, the distance between the buttons of said band being less than that between said button-holes whereby said band is free to be extended until its length equals the distance between said last-mentioned slits.
15. 5. An inner garment adapted to be supported from the waist and hips of a wearer, an outer garment adapted to be supported from the waist of a wearer and to be superimposed on said inner garment, a constricting element secured to one 20 of said garments and adapted to constrict the girth thereof at its waist encircling portion for the purpose of supporting said garment from the waist of the wearer, said element comprising an elastic band carrying a button at each end 25 and secured to said last mentioned garment at an intermediate portion of said band, registering openings in said garments on each side of the secured portion of said band permitting passage of the ends thereof through the garments, and 30 registering button-holes in said garments positioned outwardly of said aforementioned portion in relation to said secured portion of the band and adapted to receive one of the buttons on said band, the distance between said button-holes 35 measured along the garment being greater than that between the buttons measured along the band, whereby when said buttons engage said button-holes, the band will tend to gather in the portions of said garments between said button-holes and thereby elastically constrict the waist- 5 encircling portion of said garment.
6. An inner garment adapted to be supported from the waist and hips of the wearer, an outer garment adapted to be supported from the waist of the wearer and to be superposed on said inner 10 garment, a constricting element secured to one of said garments and adapted to constrict the girth thereof at its waist encircling portion for the purpose of supporting said garment from the waist of the wearer, said element comprising an 15 elastic band secured to said last mentioned garment and having a free end portion, a button carried by said free end portion, registering openings in said garments adapted to permit the passage on the free end of the band therefrom and 20 registering buttonholes in said garments adapted to receive said button, said openings being located intermediate said buttonholes and the secured end of said band, the distance between said buttonholes and said secured portions of the band 25 measured along the garment being greater than that between the button and the secured end of the band measured along the band, whereby when said buttons engage said button holes, the band will tend to gather in the portions of said 30 garments between said buttonholes and thereby elastically constrict the waist-encircling portion of said garment.

BETTY RUBIN.
